COUNTERBALANCE MECHANISM

Edwin E. Foster, Austin, Tex.

Application January 6, 1947, Serial No. 720,352

10 Claims. (Cl. 16—198)

1

This invention relates to a window or door counterbalance mechanism of the type arranged at the top of the window or door frame, and operative by coiling or uncoiling a spring.

It is, therefore, an object of the invention to provide positive means to shift the counterbalance mechanism as the window is raised or lowered. Another object resides in the provision of a screw and nut device on a shaft to positively shift the mechanism as the window is raised or lowered.

A further object resides in the provision of a shaft having a coiled spring thereon to act as counterbalance means, and screw threaded means on the shaft to shift the latter for the purpose of maintaining the cords or cables connected to the window in vertical alignment.

Further objects will be apparent from the following description, when considered in connection with the accompanying drawing in which:

Figure 1 is a front elevation of the counterbalance mechanism applied to a window, and window frame.

Fig. 2 is a plan view of the mechanism on a large scale with certain parts in section,

Fig. 3 is a perspective view of one of the supporting brackets,

Fig. 4 is a side view of one of the bearing members,

Fig. 5 is an end view of the bearing of Fig. 4, and

Fig. 6 is a side view of an anchor or bearing device.

The invention is illustrated as applied to a window, but the invention may also be applied to a door or any other opening and closing member which is to be counterbalanced, such as a screen, etc. The window frame 1 may be constructed of wood or metal having relatively narrow vertical members 3 and a top member 9. As a double sash window with two sliding frames, Fig. 1 shows the upper sash 10 having a glass pane 11. Any means may be employed to retain the window sashes in the frame, such as the well known side strips along the vertical and horizontal parts of the window frame.

The counterbalance mechanism is applied on the upper or top frame member 9, and is supported on two supporting brackets 12, each having two partial slots 14 and 15 therein for the upper and lower sashes. Each bracket 12 is suitably held in place on the frame member 9 by means of screws 16 which pass through holes 17 in the right angle brackets. Each bracket 12 has a base portion 18 in which the screw holes

2

17 are provided, and a right angle portion 19 in which the slots 14 and 15 are provided, slots 14 for one window pane, and 15 for the other pane.

A shaft 20 is rotatably supported in the brackets 5 having a bearing 21 preferably of brass at the right end, and a bearing 22 at the left end. The bearing 22 is provided with screwthreads 23 and a pair of key slots 24 which latter fit into the slot 15 of the portion 19 of the bracket 12. The bearing 21 has a pair of key slots 25 which likewise fit into the slot 15 of its bracket 12. The bearing 21 also has an integral sleeve 26. On each end of the shaft 20 there is secured a cone shaped pulley or drum 27 and 28 each having a spiral groove 15 29 thereon. Adjacent the pulley 27 there is provided a screwthreaded sleeve 30 on the shaft 20 and having screwthreads 31 and secured to the shaft 20 by means of a pin 32. The external screwthreads 31 of the sleeve 30 mesh with the internal threads 23 of the bearing nut 22. There is also provided on the shaft 20 a retaining and adjustment sleeve 33 having a section 34, two or more such as four radial holes 35 in a section 44 and a section 36 with longitudinal perforations or slots 45 therein through which a cotter pin 37 or the like may extend through the section and through a hole in the shaft, as shown in Fig. 2. A right hand wound spiral spring 38 is secured on the sleeve sections 34 and 28.

30 The window sash 10 is connected to the counterbalance device by means of cables 39 secured at one end 40 to the window frame by means of a screw 41 and the other end to its respective pulley such as by means of a screw 42 bearing against a cotter pin 43 as shown in Fig. 2.

As shown in Fig. 2, the shaft 20 is free to turn in the sleeve 26 and bearing 21, whereas the sleeve 33, 34 rotates with the shaft. Also, the cone pulleys 27 and 28 rotate with the shaft 20.

40 The operation of the device is as follows:

As the sash 10 is moved downward, the cables 39 will cause the cone spiral 29 to turn and wind up the spring 38. As the sash is lowered, the cones 27 and 28 move to the left, due to the fact that the threaded sleeve 30 operates as a screw in the stationary nut or bearing 22. Since the screw 30 is provided with the same number of threads per inch as the cone 27, the cables 39 will remain in a vertical plane and will not crawl from one side to the other. The spring 38 is loosely wound, that is, the coils are not jammed together, but preferably have a short space between each coil. Then as the spring winds, it may compress slightly or stretch slightly to adjust itself to the perfect alignment determined by the screw thread

31 and the nut 22. Where an extra short spring is used, for instance, it would have to stretch. In a window which required an extra long spring, it would need to compress or shorten the spaces between the coils. In other words, the spring still lengthens and shortens as it turns, but this condition is not utilized to guide the cable in its vertical plane. Instead, the mechanism uses a more exact means and opposing this tendency whatever amount is necessary. The spring also has less friction when the coils are not touching each other.

In order to assemble this device, the spring is completely free—that is, in its normal, unwound position, and the pin 37 is out of the hole in the shaft 20. The sash is placed in the window at its bottom position and the cables 39 are extended down through the holes in the frame, and attached to the sash by means of the nails or screws 41. The brackets 18 and 19 are identical and are positioned and fastened to the top window frame 9. The winding nut 44 is then wound by means of two nails fitting in the holes 35 until the spring is sufficiently strong to lift the sash. The pin 37 is then inserted through the slots 45 and the hole in the shaft 20. The number of turns can be counted and a chart made to correspond to a certain weight sash. Also, calibrations can be made on the edge of the slots 45 to line up with the pin 37 to indicate the approximate position to which it should be wound.

It is thus apparent that as the sash is moved up and down, the shaft 20 is shifted longitudinally, due to the screw threads 34 on the sleeve 30, and thus the cables 39 will always be maintained in a vertical position. Also, the cone-shaped pulleys 21 and 23 will compensate for the slight change in the tension in the spring as the leverage changes on the spiral track of the cones.

It will be noted that the coils of the spring 20 are shown in spaced relation, rather than in contact with each other, and this is preferable, since the spring acts when it is twisted. Thus, the spring is provided with an initial tension in the relatively unwound position when the sash is closed. In a spring with the coils touching each other, such springs are made with a longitudinal tension as well as a circular tension, when the spring is coiled, resulting in considerable friction, due to the sides of the coils rubbing on each other. The spring according to this invention stands only a twist, and the actual shifting of the pulleys and shaft is accomplished by means of the threaded sleeve 30 and the nut 22.

I claim as my invention:

1. A counterbalance mechanism for windows and the like comprising a shaft having a pulley at each end, a bracket on each side of a window frame, a pair of bearings for the shaft mounted in a stationary relationship in each bracket, and means on the shaft at at least one bearing to shift the shaft when the window is raised or lowered.

2. A counterbalance mechanism for windows and the like comprising a shaft having a pulley at each end, a bracket on each side of a window frame, a pair of bearings for the shaft mounted in a stationary relationship in each bracket, and a threaded sleeve secured on the shaft at at least one bearing to shift the shaft when the window is raised or lowered.

3. A counterbalance mechanism for windows and the like comprising a shaft having a pulley at each end, a bracket on each side of a window frame, a pair of bearings for the shaft mounted

in a stationary relationship in each bracket, means on the shaft at at least one bearing to shift the shaft when the window is raised or lowered, and a spring secured at one end to the shaft, and the other end to the other bearing to counterbalance the window sash.

5. A counterbalance mechanism for windows and the like comprising a shaft having a pulley at each end, a bracket on each side of a window frame, a pair of bearings for the shaft mounted in a stationary relationship in each bracket, means on the shaft at at least one bearing to shift the shaft when the window is raised or lowered, and a spring secured at one end to the shaft, and the other end to the other bearing to counterbalance the window sash, said spring having a plurality of coils which are spaced from each other.

10. 6. A counterbalance mechanism for windows and the like comprising a pair of brackets mounted in spaced relation on the top of a window frame, a bearing member mounted in a stationary manner in each bracket, one bearing having a sleeve extension, a sleeve mounted in the other bearing in threaded relationship therewith, a shaft rotatably mounted in the bearing with the sleeve extension and in the threaded sleeve by a pin connection, an adjustable sleeve mounted on the shaft to rotate therewith, and having an extension thereon, a coil on the shaft connected at one end to the adjustable sleeve, and the other end on the sleeve extension, and a pulley on each 15 end of the shaft, each connected by a cable to a sash of the window, movement of the window causing a rotation of the pulleys and shaft and the screwthreaded connection of the threaded bearing and its threaded sleeve causing a lateral shifting of the shaft and pulleys.

20. 7. A counterbalance mechanism for windows and the like comprising a pair of brackets mounted in spaced relation on the top of a window frame, a bearing member mounted in a stationary manner in each bracket, one bearing having a sleeve extension, a sleeve mounted in the other bearing in threaded relationship therewith, a shaft rotatably mounted in the bearing with the sleeve extension and in the threaded sleeve by a pin connection, an adjustable sleeve mounted on the shaft to rotate therewith, and having an extension thereon, a coil on the shaft connected at one end to the adjustable sleeve and the other end on the sleeve extension, a pulley on each end of the shaft, each connected by a cable to a sash of the window, movement of the window causing 25 a rotation of the pulleys and shaft, and the screwthreaded connection of the threaded bearing and its threaded sleeve causing a lateral shifting of the shaft and pulleys, and means for adjusting and locking the adjustable sleeve on the shaft.

30. 8. A counterbalance mechanism for windows and the like comprising a pair of brackets mounted in spaced relation on the top of a window frame, a bearing member mounted in a stationary manner in each bracket, one bearing having a sleeve extension, a sleeve mounted in the other bearing in threaded relationship therewith, a shaft rotatably mounted in the bearing with the sleeve extension and in the threaded sleeve by a pin connection, an adjustable sleeve mounted on the shaft to rotate therewith, and having an extension thereon, a coil on the shaft connected at one end to the adjustable sleeve, and the other end on the sleeve extension, a pulley on each end of the shaft, each connected by a cable to a

sash of the window, movement of the window causing a rotation of the pulleys and shaft and the screwthreaded connection of the threaded bearing and its threaded sleeve causing a lateral shifting of the shaft and pulleys, and means for adjusting and locking the adjustable sleeve on the shaft, the coils of the spring being in spaced relation relative to adjacent coils.

8. In a counterbalance mechanism for windows and the like having a coil spring mounted on a rotatable shaft with a pulley at each end connected to a window sash, positive means for shifting the shaft and pulleys axially as the window sash is raised and lowered.

9. In a counterbalance mechanism for windows and the like having a coil spring mounted on a rotatable shaft with a conical pulley at each end connected by a cable to a window sash, posi-

tive means including a screwthreaded connection for shifting the shaft and pulleys axially as the window sash is raised and lowered.

10. In a counterbalance mechanism for windows and the like having a coil spring mounted on a rotatable shaft with a conical pulley at each end connected by a cable to a window sash, positive means including a screwthreaded connection for shifting the shaft and pulleys axially as the window sash is raised and lowered, said means including an externally threaded sleeve secured on the shaft and an internally threaded bearing nut secured on a bracket with the threaded portions cooperating with each other to shift the shaft.
